UNITED STATES PATENT OFFICE.

LEWIS W. OWEN, OF BERGHLZ, OHIO.

RAIL-JOINT.

1,117,514.

Specification of Letters Patent. Patented Nov. 17, 1914.

Application filed September 9, 1913. Serial No. 788,868.

To all whom it may concern:

Be it known that I, LEWIS W. OWEN, citizen of the United States, residing at Berg-
holz, in the county of Jefferson and State of
Ohio, have invented certain new and useful
5 Improvements in Rail-Joints, of which the
following is a specification.

The present invention relates to new and
useful improvements in rail joints, and con-
10 templates the provision of a device of this
character which is simple in construction,
being formed of a minimum number of
parts, may be cheaply manufactured, will
be durable and adequately efficient in its
15 action, and may be readily applied to hold
the abutting ends of standard rails in the
desired position upon a tie with all nec-
essary firmness and rigidity.

An object of equal importance with the
20 foregoing is to construct the joint of this
invention in such manner that it may be
applied to the abutting ends of rails and
completely assembled in operative position
25 with a minimum expenditure of time and
labor, thus facilitating in a large measure
the work of replacing broken rails, joints or
damaged ties.

A still further object is to construct a rail
joint consisting broadly in a pair of slid-
30 ably connected tie plates which carry fish-
plates adapted to bear against the web por-
tions of the abutting rail terminals and the
adjacent base portions of the rails, effectu-
35 ally holding the rail ends against transverse
or vertical movement.

A yet further object is to equip one of the
fish-plates with inwardly projecting studs
or bolts which are insertible through the
40 bolt receiving apertures commonly formed
in the webs of rail terminals, and are formed
with grooves or slots adjacent their free or
innermost ends which slots are adapted to
45 receive locking lips or ribs carried by the
second fish-plate and formed to co-act with
a longitudinally extending slot in holding
the studs or bolts of the first fish-plate
50 against withdrawal from the web portions
of the abutting rail ends.

A yet further object is to construct the
50 base or tie-plate portion of the device with
a sliding connection, so that the stud carry-
ing portion of the device may be applied to
the abutting rail terminals in relatively
fixed relation thereto, and the other section
55 or portion of the device may be placed on
one of the rails and slid longitudinally

thereon to bring the terminals of the studs
in a receiving slot and to dispose the lips
or ribs in the grooves of the studs, at the
same time completing the sliding connection 60
between the base plate portions of the two
sections, so that the fish-plates carried by
the two sections will engage against the
opposite faces of the rail webs.

The above and additional objects are ac-
complished by such means as are illustrated
in the accompanying drawings, described in
the following specification, and then more
particularly pointed out in the claims with
are appended hereto and form a part of this 70
application.

With reference to the drawings, wherein
I have illustrated the preferred embodiment
of my invention as it is reduced to practice,
and throughout the several views of which 75
similar reference numerals, designate corre-
sponding parts, Figure 1 is a perspective
view of the rail joint in assembled relation
to the abutting terminals of a pair of rails;
Fig. 2 is a bottom plan view; Fig. 3 is a 80
longitudinal section of the joint taken
through the web portion of the rail in a
horizontal plane; Fig. 4 is a transverse sec-
tional view; Fig. 5 is a detail perspective
view of one section of the joint; and Fig. 85
6 is a detail perspective view of the other
section of the joint.

Before proceeding to the description of
the drawings, it is desirable to emphasize
the fact that great difficulty has heretofore 90
been encountered in the application of rail
joints to the abutting terminals of the rails
in that the bolts commonly employed in
connection with fish-plates or the like must
be singly applied, involving considerable 95
time and labor. This invention, therefore,
aims to overcome this needless expenditure
of time and labor by providing one of the
fish-plates with relatively fixed studs which
may be of any desired number and may be 100
simultaneously inserted through the receiv-
ing apertures in the fish-plates.

Proceeding now to the description of the
drawings, the numerals 10 and 11 designate
respectively and as entireties the two sec- 105
tions which, when in assembled position,
constitute a rail chair. Each section in-
cludes a base portion and a side wall por-
tion. The base portion and side wall por-
tion of each section form in reality tie- 110
plates and fish-plates, as will be hereinafter
more fully disclosed.

Taking up now particularly the description of the section 10 which, when in assembled position, is fixed in its relation to the rails as regards longitudinal movement, this element includes, as best illustrated in Fig. 5, a base portion or tie-plate 12 and a fish-plate 13, which are preferably formed integrally, and may be of cast-steel or any other desired and suitable material which 5 may be found most efficient under the conditions concurrent with the application of the invention. The tie-plate portion 12 is substantially oblong in shape, and is of such width that its upper face, indicated 10 at 14, is approximately equal in width to the standard rail base, while its outer longitudinal edge lies remote from the adjacent edge of the rail base such a distance 15 as will afford the desired supporting surface. As will be readily observed upon reference to Fig. 5, the lower edge of the fish-plate 13 merges into the tie-plate 12 at the outer longitudinal edge thereof, thus producing a thickened portion. This thickened 20 portion is formed with a number of notches or recesses, which are indicated at 15, and are provided for the obvious purpose of applying spikes to the tie-plate, whereby it may be held in the desired position on the 25 tie.

The under face of the member 12 is formed with a longitudinally extending centrally disposed slot or groove, indicated at 16. The member 12 is further cut-away, as 30 at 17, from the slot 16 to the inner edge 18. This cut-away portion 17 and slot 16 are provided for a purpose which will be hereinafter fully disclosed in that portion 35 of the specification devoted to the description of the application of the two sections of the joint to the abutting ends of the rails. The inner edge 19 of the slot 16 is undercut, also for a purpose to be hereinafter 40 fully described.

The fish-plate 13 of the section 10 conforms on its inner face to the outline of the rail base and rail web, so that when the section 10 is in assembled position, the fish-plate 13 will snugly engage against the upper face of the rail base and the adjacent 50 face of the rail web.

Referring now particularly to Fig. 5, it will be noted that a number of studs 20 project from the inner face of the member 13 55 and are arranged in a longitudinally extending series, being longitudinally spaced from each other. These studs are of such length that when inserted through the receiving apertures 21 formed in the rail webs, 60 their ends will project a slight distance beyond the opposite faces of the rail webs.

The free terminals of the studs which, as described, are designed to extend beyond the opposite face of the rail web, are formed 65 with diametrically opposed grooves, indi-

cated at 22 and 23. These grooves are arranged in such manner that their bottom walls lie in a horizontal plane parallel with the plane of the rail base, adapting them for the reception of locking lips or ribs 70 which are carried by the fish-plate of the section 11, as will be described in detail hereinafter.

At this point, it is desirable to direct 75 attention to the fact that the stud receiving apertures formed in the rail webs are preferably elliptical in shape, being arranged with the longitudinal axes of the ellipses in horizontal planes, the purpose of this formation of these stud receiving apertures being to permit the expansion and contraction of the rails.

Coming now to the description of the 80 slideable section 11 of the rail joint; this element includes a tie-plate or base portion 85 25 and a fish-plate 26. The tie-plate 25 is in shape substantially similar to the member 12, but is of less width. The inner edge 27 of this member 25 extends slightly beyond the longitudinal center of the rail 90 base when in assembled position, and is equipped with an integrally formed rib or strip 28 which is produced by making a longitudinally extending slot or groove 29 in the upper face of the member 25. This 95 feature of the invention is best illustrated in Fig. 6, to which reference is now had. The inner edge 30 of the member 28 is undercut, so that when the member 28 is inserted within the slot 16, the undercut edge 100 of the slot and the undercut edge of the member 28 will engage and prevent the displacement of the rib 28. In this connection, it is to be observed that the inner face 105 of the fish-plate 26 is formed with a longitudinally extending slot 31, the edges of which are defined by a pair of longitudinally extending lips or ribs 32. The adjacent edges of these lips 32 extend in parallel 110 spaced relation to each other and comprehend a distance less than the width of the slot 31, as will be readily observed upon reference to Fig. 6. The purpose of this slot 31 and the lips 32 will be apparent when 115 reference is had to Fig. 4. In this figure, it will be noted that the lips 32, when in assembled relation, are seated in the grooves 22 and 23 of the studs 20, while the extreme 120 terminals of the studs lie within the slot 31. By this means, the studs are securely held against withdrawal from the rail webs. It is to be noted at this point that the slot 31 does not extend throughout the length 125 of the fish-plate 26, but terminates a short distance from one terminal thereof to form a stop shoulder, the obvious purpose of such formation being to limit the sliding movement of the section 11 when the rail joint is assembled.

Referring now particularly to Figs. 2 and 130

3, it will be observed that the slot 16 formed in the underface of the fish-plate 12 extends diagonally with respect to the longitudinal axis of the fish-plate. Obviously, therefore, 5 the straight edge 19' and the undercut edge 19 of this slot being parallel to each other throughout their length also extend diagonally with respect to the longitudinal axis of the fish-plate 12. The undercut edge 30 of the rib 28 likewise extends diagonally with respect to the longitudinal axis of the member 25. It will, therefore, be apparent that 10 when the two sections of the rail joint are slid into home position, the diagonal disposition of the receiving slot 16 and the edge 30 of the rib 28 will act to move the adjacent faces of the fish-plates 13 and 26 in toward each other, at the same time maintaining 15 them in parallel spaced relation. In this connection, it is to be noted that the edge 30 of the rib 28 and the edges of the slot 16 are oppositely directed as regards their angular 20 relation to the longitudinal axes of the fish-plates 26 and 13 for, as will be readily observed upon reference to Fig. 2, the edge 30 is spaced from the outer edge of the fish-plate 25 the greatest distance at that end of 25 the rail joint at which the undercut edge 19 of the slot 16 is least removed from the outer edge of the fish-plate 13. Obviously, therefore, as well as bringing the two fish-plates 30 into closer engagement against the web of the rail, the peculiar formation of the slot 16 and edge 30 acts to wedge the sliding joint of the two tie-plates when the sections 35 are slid into home position, in the manner to be hereinafter described.

The actual construction and arrangement 40 of the various elements of the two sections 10 and 11 being thus described in detail, it now remains to describe in brief the method followed when the sections are applied to the adjoining terminals of the rails and to direct 45 attention to the peculiar advantages resultant from the novel form of structure employed. In applying these sections 10 and 11, the member 10 is first disposed on the tie with the base or tie-plate portion 12 resting on the upper face of the tie. The rail terminals are then disposed on the upper face of 50 the member 12 and are slid transversely thereof to project the studs 20 through the receiving apertures formed in the rail webs. When the rail terminals are thus applied, it 55 is obvious that they will be supported by the upper face of the tie-plate 12, while the fish-plate will snugly engage against the upper face of the rail base and adjacent face of the rail web. It is also to be noted that the upper edge of the fish-plate 13 will engage 60 against the under portion of the rail tread.

Following the operation above described, it remains to apply the section 11. In this 65 operation, the tie-plate 25 is disposed beneath the lower face of the rail base of one

rail and the fish-plate 26 is disposed in engagement with the upper face of the rail base and adjacent face of the rail web. The section 11 is then slid longitudinally of the rail to bring the lips 32 into receiving grooves 21 70 and 22 of the studs, while the rib or strip 28 is inserted into the receiving slot 16. When the sliding section 11 is moved into home position, it only remains to apply spikes in the notches 15 of the members 12 and 25. 75 The rail joint is thus complete.

Relative to the many advantages resultant from the novel form of structure herein described and illustrated, it is to be noted first of all that this invention provides what may 80 be termed a boltless rail joint since it is not necessary to apply individual bolts or similar fastening devices to the fish-plates in order to hold the terminals in the desired position. It is also desirable to direct attention to the extreme simplicity of the rail joint, which is believed to be one of the chief 85 merits of this invention. It is also desirable to emphasize the fact that the rail joint of this invention permits the removal of rail 90 or the substitution of ties with a minimum expenditure of time and labor, inasmuch as the operation of assembling the rail joint involves merely the withdrawal of the tie spikes and the sliding of the section 11 along 95 the rail.

In reduction to practice, I have found that the form of my invention, illustrated in the drawings and referred to in the above description as the preferred embodiment, is the 100 most efficient and practical; yet realizing that the conditions concurrent with the adoption of my device will necessarily vary, I desire to emphasize the fact that various minor changes in details of construction, 105 proportion and arrangement of parts may be resorted to, when required, without sacrificing any of the advantages of my invention, as defined in the appended claims.

What I claim is:—

1. The combination with abutting rail terminals, of a chair spanning the junction of said rail terminals and including mating sections having interlocking base portions and each provided with an upstanding side 115 wall, the inner face of the side wall of one section being formed with a longitudinally disposed slot opening through one end thereof and terminating short of the other to form a stop shoulder, said slot defining 120 inwardly projecting lips, the free edges of which are disposed parallel with each other and extend uninterruptedly from the shoulder to the open end of the slot, and studs extending laterally from the inner face of the 125 side wall of the mating chair section and having their upper and lower faces provided with transverse grooves adapted to receive the lips when the chair sections are assembled in position on the rail terminals. 130

2. The combination with abutting rail terminals, of a chair embracing the rail terminals at the junction thereof and formed of mating sections, each provided with an upstanding wall and an inwardly extending base portion, the base portion of one chair section being provided with an undercut rib adapted to enter a correspondingly undercut slot formed in the base portion of the 5 mating chair section, the inner face of the side wall of one of the sections being provided with a longitudinally disposed slot opening through one end thereof and terminating short of the other end to form a 10 stop shoulder, said slot defining inwardly projecting lips, the free edges of which are disposed parallel with each other and extend uninterruptedly from the shoulder to the open end of the slot, and spaced cylindrical 15 studs projecting laterally from the inner face of the side wall of the mating chair section and having transverse grooves formed in the top and bottom thereof and adapted to receive the lips when the chair is assembled in 20 position on the rail terminals.

3. The combination with abutting rail terminals, of a chair embracing the rail terminals at the junction thereof and formed of mating sections, each section being provided with an upstanding side wall and an inwardly projecting base portion, the base portion of one chair section being provided with a diagonally extending rib adapted to enter a correspondingly shaped groove 30 formed in the base portion of the mating section, the face of the side wall of one of the chair sections being smooth and unobstructed and provided with a longitudinally disposed slot opening through one end of the side wall 35 and terminating short of the other to form a stop shoulder, said slot defining inwardly projecting lips extending in spaced parallel relation to each other from the shoulder to the open end of the slot and having their 40

free edges smooth and unobstructed throughout their entire length, and studs projecting laterally from the inner face of the side wall of the mating section and having upper and lower transverse grooves formed therein and adapted to receive the lips when the chair is 50 assembled in position on the rail terminals.

4. The combination with abutting rail terminals, of a chair embracing the rail terminals at the junction thereof and formed of mating sections, each provided with an inwardly extending base portion having means for interlocking engagement with the base portion of the mating section, said chair sections being formed with upstanding side walls adapted to bear against the webs of 55 the rail terminals, the inner face of the side wall of one of the chair sections being formed midway of its upper and lower longitudinal edges with a longitudinally disposed slot opening through one end of the side wall 60 and terminating short of the other to form a stop shoulder, said slot defining inwardly projecting lips forming a partial closure for the slot and having their free edges disposed parallel and continued uninterruptedly in 65 70 parallel relation from the shoulder to the open end of the slot, and cylindrical studs projecting laterally from the inner face of the side wall of the mating chair section and having upper and lower transverse grooves 75 formed therein adapted to receive the lips when the chair is assembled in position on the rail terminals, one of the studs, by engagement with the stop shoulder, serving to limit the longitudinal movement of the chair 80 on the rails.

In testimony whereof I affix my signature in presence of two witnesses.
